UNITED STATES PATENT OFFICE.

LOUIS DE S. DIBERT AND ROBERT C. WINTER, OF PHILADELPHIA, PENNSYLVANIA.
TRANSPOSING DEVICE FOR PNEUMATIC MUSICAL INSTRUMENTS.

1,394,541.

Specification of Letters Patent.

Patented Oct. 25, 1921.

Application filed June 15, 1920. Serial No. 389,236.

To all whom it may concern:

Be it known that we, LOUIS DE S. DIBERT, Philadelphia, county of Philadelphia, Pennsylvania, and ROBERT C. WINTER, Philadelphia, county of Philadelphia, Pennsylvania, have jointly invented certain new and useful Improved Transposing Devices for Pneumatic Musical Instruments, of which the following is a specification.

10 The purpose of the present invention is to shift a device with respect to the tracker-bar of a mechanical musical instrument for transposing music from one key to another.

It consists in the elements and features of 15 construction shown and described as indicated in the claims. In the drawings:

Figure 1, is a fragmentary view, in vertical section, illustrating so much of a player piano as is necessary to an understanding 20 of the invention and showing in application thereto one embodiment of the present invention.

Fig. 2, is a view in horizontal section of 25 a part of the apparatus shown in Fig. 1.

Fig. 3, is a fragmentary view in front elevation of Fig. 2.

Fig. 4, is a similar view of the rear of Fig. 2, and

Figs. 5, and 6 are fragmentary views 30 illustrating a modified form of construction.

Referring now to the drawings in detail, 10 designates the casing of a mechanical musical instrument, 11 a tracker-bar, 12 a music sheet, and 13 a take-up spool. The 15 music sheet roll has been omitted for the sake of clearer illustration. These parts may be of any standard type. In such an instrument tubes connect the ducts in the tracker-bar with the usual pneumatics as is well understood in the art. According to the present invention the transposing device may be added to existing instruments, new or old, without change of parts other than severing of the said tubes and connecting the device, 40 about to be described, between the severed ends of the tubes. Obviously in the manufacture of new instruments two sections of tubing for each key are employed instead of a single piece of tubing, one section of 45 tubing leading from the tracker bar to said device and the other leading from said device to the pneumatics. The transposing device of the invention is preferably located adjacent the tracker bar 11 and to one side 50 of the music sheet 12. It is shown as being mounted upon a support 14 carried by the

casing 10 and generally stated comprises a pair of fixed, spaced plates 15 and 16 and a rotatably mounted disk 17 which is shiftable toward and away from the plate 16, 60 the plate 16 and disk 17 being provided with registering ducts to which the respective severed ends of said tubes are connected. Mounted in the plates 15 and 16 is a rotatable shaft 18 fixed to one end of which is 65 the disk 17 and fixed to the opposite end of which is a pointer 19. The shaft is capable of slight endwise movement through said plates and a spring 20 normally tends to draw the disk 17 toward the plate 16. The 70 disk 17 and plate 16 are provided with a plurality of ducts disposed concentrically with the shaft 18. The ducts of the disk 17 consist of short sections of hollow stems 21 provided with rubber cups 22. The 75 ducts of the plate 16 consist of short, hollow stems 23, provided with collars 24 and nipples 25. The nipples 25 are normally seated in the rubber cups 22, by reason of spring 20. Additional springs as 26 are 80 provided one for each hollow stem 21, to insure against any unevenness in the length of said nipples or any irregularity in position of plates 16 and 17. The collars 24 limit the outward movement of the stems 85 23. Tubes 27 connect the tracker-bar with stems 23 and tubes 28 connect the stems 21 with the usual pneumatics. In order that the disk 17 may be fixed in registered positions of the ducts and so that the rubber cups 22 90 may be seated evenly with respect to nipples 25; pins 29 and apertures 30 are provided for each duct. In the drawings the pins are shown as being mounted upon the disk and the apertures provided in the plate 16 95 for illustrative purposes. The front of plate 15 is provided with a scale so that the operator may readily shift the pointer to obtain the desired higher or lower key. The manner of shifting the disk 17 is as 100 follows:—The operator first pushes, in the direction of the arrow in Fig. 1, the shaft 18 against the spring 20 so that the pins 29 are free of apertures 30 and the stems 21 free of nipples 25. The pins 29 are long 105 enough to insure clearance of nipples 25 before disk 17 can be turned. This position is shown in Fig. 2. The operator now shifts to the left or right, to obtain a lower or higher key as desired, the pointer 19 whereupon the ducts of disk 17 may be caused to register with proper ducts of plate 16. 110

When the pointer 19 has been turned to the mark indicating the required number of half tones above or below the normal key, pressure on shaft 18 is released whereupon disk 17 returns to operative position with a different set of ducts in register with the result that notes of a lower or higher pitch are produced. Upon the disk 17 the duct normally leading from the highest tone 10 upon the instrument is designated 32 and that denoting the lowest tone 33. Between these two ducts are a plurality of "blank" ducts 34 any number of which may be employed. The plate 15 is correspondingly 15 graduated and the graduation indicated by the same reference numerals in the drawings. The "blank" ducts 34 are necessary so that certain ducts of plate 16 will not be left open when the disk 17 is partially rotated to obtain a higher or lower key.

Referring now to Figs. 5 and 6 a modified form is disclosed. Instead of having a rotatable disk to obtain transposition of notes use is made of a longitudinally and laterally 25 shiftable member 50. This member is provided with hollow stems and rubber cups as in the above described disk 17 and tubes lead therefrom to the pneumatics. The tracker-bar ducts are provided with nozzles 35 for seating within said cups as the member 50 is shifted toward the tracker-bar. A spring pressed push-rod 36 is present for moving the member away from the tracker-bar. This push-rod is mounted in an endwise 30 slideable member 37 which has tongued and grooved relation with a supporting structure 38 below the tracker-bar. When the member 50 is moved away from the tracker-bar by means of push-rod 36 a tongue 39 is disengaged from a rack-bar 40 so that the members 37-50 may be shifted 45 endwise along the tracker-bar for raising or lowering the key as before described. It may be stated that the rack-bar 40 is provided with notched portions 41 (the spacing of notches being the same as spacing of ducts in the tracker-bar) for locking the ducts of members 50 in register with the ducts of the tracker-bar. The number of 50 notches in rack-bar 40 depends upon the number of half tones up or down that the device is to cover. This device also possesses the advantage of being capable of application to existing mechanical musical instruments.

For illustrative purposes and for the sake of clearness but one set of tubes 27-28 and complementary connecting parts have been shown in connection with plate 16 and disk 60 17 in Fig. 1, and in Fig. 2, but two sets have been shown for the same reason.

While we have illustrated and described certain particular embodiments of our invention, it will, of course, be understood that we 65 do not wish to be limited to the exact con-

struction shown and described, but the various modifications and changes will readily suggest themselves to those skilled in the art without departing from the scope of the invention as set forth in the appended 70 claims.

What we claim is:-

1. In an automatic musical instrument the combination of a tracker-bar and a pneumatic action with a transposing device 75 consisting of a fixed member and a movable member each provided with equally spaced air ducts, means connecting the ducts of the tracker-bar with the ducts of one of said members, means connecting the ducts of the 80 other of said members with the pneumatic action, means for shifting the movable member away from the fixed member to disengage registration of said ducts, and means for shifting the movable member with respect to 85 the fixed member in a plane parallel thereto to obtain alinement of proper ducts for transposing purposes.

2. A construction as described in claim 1, characterized by the movable member being 90 mounted upon an endwise shiftable and cushioned rod.

3. A construction as described in claim 1, characterized by the movable member being provided with a plurality of "blank" ducts 95 intermediate those ducts normally leading from the highest and lowest tones.

4. A construction as described in claim 1, characterized by spring controlled hollow stems mounted in the ducts of one of said 100 members.

5. A construction as described in claim 1, characterized by hollow stems equipped with cups of yielding material mounted in the ducts of one of said members.

6. In an automatic musical instrument the combination of a tracker-bar and a pneumatic action with a transposing device comprising a fixed member, a rotatably mounted member each provided with equally spaced 110 air ducts disposed upon an arc of a circle, tubes connecting the ducts of the tracker-bar with the ducts of the fixed member, flexible tubes connecting the ducts of the rotary member with said pneumatic action, a 115 cushioned rod supported by the fixed member and upon which the rotatable member is fixed, a pointer fixed to said rod for indicating the extent to which the movable member is rotated and means between said movable and fixed member for relatively securing said members together with said ducts in register.

7. In an automatic musical instrument the combination of a tracker-bar and a pneumatic action with a transposing device comprising a fixed member and a rotatably mounted member each provided with equally spaced air ducts disposed upon an arc of a circle, tubes connecting the ducts of the 120 125 130

- tracker-bar with the ducts of one of said members, tubes connecting the ducts of the other member with said pneumatic action, a cushioned rod supported by the fixed member and upon which the rotatable member is 5 fixed, a pointer fixed to said rod for indicating the extent to which the movable member is rotated and means between said movable and fixed member for relatively securing said members together with said ducts in 10 register.

LOUIS DE S. DIBERT.
ROBERT C. WINTER.
